UNITED STATES PATENT OFFICE.

JULIUS P. HEIL, OF MILWAUKEE, WISCONSIN.

FLUID HOIST.

1,421,469.

Specification of Letters Patent. Patented July 4, 1922.

Application filed April 2, 1919. Serial No. 286,872.

To all whom it may concern:

Be it known that I, JULIUS P. HEIL, a citizen of the United States, and resident of Milwaukee, in the county of Milwaukee and 5 State of Wisconsin, have invented new and useful Improvements in Fluid Hoists, of which the following is a description, reference being had to the accompanying drawings, which are a part of this specification.

10 This invention relates to improvements in fluid hoists.

It is one of the objects of the present invention to provide a fluid hoist more particularly, although not solely, adapted for 15 operating the dump bodies of power driven trucks.

A further object of the invention is to provide a fluid hoist which may be easily used in connection with any standard make 20 of truck and dump body, and which will not require any space between the body and the cab or seat of the truck.

A further object of the invention is to provide a fluid hoist which will permit the 25 positioning of the body with relation to the front and rear axles to more evenly distribute the load thereon and thereby increase the capacity of the truck.

A further object of the invention is to 30 provide a fluid hoist in which the use of outside pipes or ducts are eliminated.

A further object of the invention is to provide a fluid hoist which is a unitary structure and self contained and has therefore 35 a minimum number of parts and may be easily mounted on a truck.

A further object of the invention is to provide a fluid hoist which will automatically stop the further tilting of the truck 40 body when said body has reached its predetermined dumping inclination.

A further object of the invention is to provide a fluid hoist in which the pumping means may continue to operate without further 45 elevation of the dump body of the truck when said dump body has reached its predetermined angle of unloading.

A further object of the invention is to provide a fluid hoist in which the truck body 50 may be elevated to and be maintained in its upper position for an indefinite period while the parts continue to operate without injury to the hoist.

A further object of the invention is to 55 provide a fluid hoist in which a plurality of

cylinders and pistons are used for elevating the truck body.

A further object of the invention is to provide a fluid hoist in which the piston itself serves to automatically stop the supply of the fluid medium to the pump when said piston has reached a predetermined position of rest.

A further object of the invention is to provide a fluid hoist which is of simple construction, is strong and durable and is well adapted for the purpose described.

With the above and other objects in view the invention consists of the improved fluid hoist and its parts and combinations as set 70 forth in the claims, and all equivalents thereof.

In the accompanying drawings in which the same reference characters indicate the same parts in all of the views:

Fig. 1 is a side view of the rear portion of a motor truck provided with the improved fluid hoist, parts being broken away and the body portion being shown in tilted position by dotted lines:

Fig. 2 is a transverse sectional view taken on line 2-2 of Fig. 1, of the improved fluid hoist;

Fig. 3 is a vertical sectional view of one of the cylinders taken on line 3-3 of Fig. 2;

Fig. 4 is a vertical sectional detail view on a larger scale, of the upper end portion of one of the cylinders;

Fig. 5 is a vertical sectional detail view taken on line 5-5 of Fig. 2;

Fig. 6 is a horizontal sectional view on a smaller scale, taken on line 6-6 of Fig. 5;

Fig. 7 is a similar sectional view taken on line 7-7 of Fig. 5; and

Fig. 8 is a vertical sectional detail view on a larger scale of the transmission mechanism.

Referring to the drawings the numeral 10 indicates a portion of a motor truck, 11 the side members of the chassis or frame, 12 the cab or seat portion and 13 the tiltable load carrying body of the truck. Said body near its rear end portion is pivotally connected to the opposite side members 11 by a pivot and bracket means 14.

The improved fluid hoist 15 comprises a pair of spaced cylinders 16 connected together at their lower ends by a lower tie bar 17 and at their upper ends by a conduit member 18 and an upper tie bar 19. The up- 110

per outer portions of the cylinders are provided with outwardly projecting portions 20 having alined trunnion recesses or sockets 20' for receiving the inwardly projecting 5 trunnions 21 of the brackets 22 which rest on and are bolted to the side members 11 of the chassis. The cylinders are pivotally supported on said trunnions and depend downwardly therefrom and are provided with 10 pistons 23 reciprocally positioned therein. The pistons are mounted on the lower end portions of piston rods or tubes 24 which extend upwardly through the upper closed ends of the cylinders and are provided with 15 upper eyed ends 25. Said eyed ends are pivotally connected to the truck body beneath the bottom portion by a pivot rod 26 which extends transversely of said bottom portion and through the longitudinal rein- 20 forcing channel member 27 thereof. Said pivotal connections permit the piston rods and cylinders to tilt and aline with said pivotal connections while the truck body is traveling its arc of movement to unloading 25 position.

The cylinders are formed with lower ports 28 and upper ports 29 which respectively charge or discharge the fluid medium from the cylinders below or above the pistons. 30 The ports 28 are in communication with ducts 30 which are formed in the walls of the cylinders and lead upwardly from said ports 28 to a lower connecting and trans- versely extending pressure duct 31 formed in 35 the conduit member 18. The upper ports 29 of the cylinders are of less height than the height of the pistons and are also in communication with an upper connecting trans- versely extending pump supply duct 32 40 formed in the conduit member 18 above the duct 31. The conduit member 18 is also pro- vided with a valve bore 33 which is connect- ed to the ducts 31 and 32 by by-pass ducts 31' and 32'. A plug valve 34 extending into 45 the valve bore 33 is provided with an angular port 35 and the valve may be turned to register said port 35 with the by-pass ducts 31' and 32' and provide a communication therebetween for the flow of the fluid me- 50 dium therethrough. This valve is turned to open communication between the by-pass ducts 31' and 32' when it is desired to lower the truck body.

A rotary gear pump 36 mounted on the 55 conduit member 18 is positioned between the ducts 31 and 32 and is connected respectively to said ducts by inlet and outlet pump ports 37 and 38. The lower outlet port 38 is pro- vided with a spring actuated ball check 60 valve 38' opening outwardly from the pump. One of the gears of the pump is connected to and driven by the transmission 39 by a connecting rod or shaft 40 and the transmission of power to the pump connecting rod is con- 65 trolled by a controlling rod 41 and a lever

42. The plug valve 34 is also controlled by a rod 43 and a lever 44, both levers 42 and 44 being preferably located in the cab or adjacent the seat of the truck.

As considerable space within the cylinders 70 is required to accommodate the piston rods when they are in their innermost position less fluid medium is used when the pistons are in their inner position than when in their outer positon and to supply the varying 75 amounts a tank 45 is mounted on the upper end portions of the cylinders which is in communication with the upper end portions of said cylinders by openings or ports 46. The fluid medium flows by gravity from the 80 tank to the cylinders when the pistons are moving upwardly, and is forced upwardly into the tank by the pistons when said pis- tons are moving downwardly.

The upper portions of the cylinders also 85 have lead or starting ducts 47 formed therein which lead from the upper ends of the cylinder bores outwardly and downwardly to the upper ports 29 to initially supply the 90 fluid medium to the cylinders above the pis- tons when said pistons are in their upper position and closing the said ports 29, and it is desired to permit said pistons to descend to their lower position. Said lead or start- 95 ing ducts are provided with ball check valves 48 which open upwardly from the ports 47 and prevent the downward flow of the fluid medium therethrough.

In use the fluid hoist is mounted on a motor truck in the manner shown in Fig. 1 100 and when it is desired to dump the contents of the truck body the transmission controlling rod is operated to transmit motion from the transmission to the pump and the operation of the pump will draw the fluid me- 105 dium from above the pistons and force it into the cylinders below the pistons and raise said pistons. The upward movement of the pistons will tilt the truck body connected thereto and when the pistons have 110 reached their uppermost position they will close the upper ports 29 and thus automatically shut off the supply of fluid medium or oil to the pump. The pump may continue to operate but as its supply of oil is cut off 115 it cannot pump any more into the cylinders below the pistons and therefore the further upward movement of the pistons will au- 120 tomatically stop. This feature is very de- sirable in constructions of this kind as it 125 eliminates any danger of damage to the hoist in the event that the operator inadvertently neglects to stop the operation of the pump. The pistons will remain in their upper po- sition whether or not the pump is in opera- 130 tion. If it is now desired to lower the truck body the valve rod 43 is operated to open the valve 34 and when opened the oil in the cyl- inders can flow through the valve to the por- tions of the cylinders above the pistons and 130

thus permit the valved controlled descent of the pistons and the truck body. As the ports 29 are closed by the pistons the initial flow of oil above the pistons will be through

5 the lead or starting ducts 47 until the pistons uncover the main upper ports 29, and when uncovered the flow will be through said main ports. The speed of lowering the truck body is controlled by opening or closing

10 more or less the port of the valve.

It is to be understood that one or any number of cylinders and pistons may be used without departing from the spirit and scope of the invention.

15 From the foregoing description it will be seen that the fluid hoist is of very simple construction and may be easily mounted on a motor truck, and is well adapted for the purpose described.

20 What I claim as my invention is:

1. A fluid hoist, comprising a pair of cylinders having ports at their opposite end portions, pistons within the cylinders and between the ports of the respective cylinders

25 and having piston rods extending through the cylinders, means connecting said piston rods together, a tank in communication with both cylinders, ducts connecting the ports of the cylinders together in pairs, a pump inter-

30 secting the pairs of ducts between the respective ports thereof for moving a fluid medium within the cylinders from one side of the pistons to the other to move the pistons to predetermined positions of rest, said

35 positions of rest of the pistons closing the ports which are supplying the fluid medium to the pump and thereby automatically stopping the movement of the pistons, and a valve controlled duct in communication

40 with the ducts connecting the pairs of ducts to permit the passage of the fluid medium from one side of each piston to the other side without passing through the pump.

2. A fluid hoist, comprising a pair of cylinders having ports at their opposite end portions, a lead port in each cylinder in communication with the cylinders and with one of the first mentioned ports of each cylinder, pistons within the cylinders and be-

50 tween the ports of the respective cylinders and having ductless piston rods extending through the cylinders, means connecting said piston rods together, ducts connecting the ports of the cylinders together in pairs, a

55 pump intersecting the pairs of ducts between the respective ports thereof for moving a fluid medium within the cylinders from one side of the pistons to the other to move the pistons to predetermined positions of

60 rest, said positions of rest of the pistons closing the ports which are supplying the fluid medium to the pump and thereby automatically stopping the movement of the pistons, and a valve controlled duct in com-

65 munication with the ducts connecting the

pairs of ducts to permit the passage of the fluid medium from one side of each piston to the other side without passing through the pump.

3. A fluid hoist, comprising a pair of 70 spaced cylinders having ports formed in their upper and lower end portions, pistons within the cylinders and between the ports of the respective cylinders and having duct-

less piston rods extending through the cyl- 75 inders, means connecting said piston rods together, a duct member connecting the cylinders together and having ducts which connect the upper and lower ports together

in pairs, a pump intersecting the duct mem- 80 ber ducts for pumping a fluid medium within the cylinders from one side of the pistons to the other to move the pistons to prede-

termined positions of rest, said positions of 85 rest of the pistons closing the ports which are supplying the fluid medium to the pump and thereby automatically stopping the movement of the pistons, and a valve controlled by-pass duct in communication

90 with the duct member ducts to permit the 90 passage of the fluid medium from one side of each piston to the other side without passing through the pump.

4. A fluid hoist, comprising a support, a 95 pair of spaced cylinders fulcrumed on the support at their upper ends and connected together at their lower ends and having ports formed in their upper and lower end portions, a tank in communication with both cyl-

100 inders, pistons within the cylinders and be- 100 tween the ports of the respective cylinders and having piston rods extending through the cylinders, a tiltable body positioned above the cylinders and connected to the upper end portions of the piston rods, a duct 105

member connecting the cylinders together and having ducts which connect the upper and lower ports together in pairs, a pump mounted on the duct member and intersect-

110 ing the ducts thereof for pumping a fluid medium within the cylinders from one side of the pistons to the other to move the pistons to predetermined positions of rest, said

115 positions of rest of the pistons closing the ports which are supplying the fluid medium to the pump and thereby automatically stop- 115

ping the movement of the pistons, and a valve controlled duct in communication with the duct member ducts to permit the passage

120 of the fluid medium from one side of each piston to the other side without passing through the pump.

5. A fluid hoist comprising a support, a 125 pair of spaced cylinders fulcrumed on the support at their upper ends and connected together at their lower ends and having ports formed in their upper and lower end portions, pistons within the cylinders and be-

130 tween the ports of the respective cylinders and having piston rods extending

through the cylinders, a tiltable body positioned above the cylinders and connected to the upper end portions of the piston rods, a duct member connecting the cylinders together and having ducts which connect the upper and lower ports together in pairs, said cylinders also having lead ports in their upper ends above the upper ports first mentioned and in communication with the ducts 5 of the duct member, a pump mounted on the duct member and intersecting the ducts thereof for pumping a fluid medium within the cylinders from one side of the pistons to the other to move the pistons to predetermined 10 positions of rest, said positions of rest of the pistons closing the ports which are supplying the fluid medium to the pump and thereby automatically stopping the movement of the pistons, and a valve controlled 15 duct in communication with the duct member ducts to permit the passage of the fluid medium from one side of each piston to the other side without passing through the pump.

6. A fluid hoist comprising a support, a 20 pair of spaced cylinders fulcrumed on the support at their upper ends and connected together at their lower ends and having ports formed in their upper and lower end portions, pistons within the cylinders and between the ports of the respective cylinders and having piston rods extending through the cylinders, a tiltable body positioned above the cylinders and connected to the upper end portions of the piston rods, a duct 25 member connecting the cylinders together and having ducts which connect the upper and lower ports together in pairs, said cylinders also having valve controlled lead ports in their upper ends above the upper 30 ports first mentioned and in communication with the ducts of the duct member, a pump mounted on the duct member and intersecting the ducts thereof for pumping a fluid medium within the cylinders from one side 35 of the pistons to the other to move the pistons to predetermined positions of rest, said positions of rest of the pistons closing the ports which are supplying the fluid medium to the pump and thereby automatically stopping the movement of the pistons, and a valve controlled duct in communication with the duct member ducts to permit the passage of the fluid medium from one side of each piston to the other side without passing through the pump.

7. A fluid hoist, comprising a support, a tiltable body mounted thereon, a pair of cylinders fulcrumed on the support at their upper ends and connected together at their lower ends and having ports formed in their upper and lower end portions, a tank connected to both cylinders, pistons within the cylinders and between the ports of the respective cylinders and having ductless piston rods extending upwardly through the 65

cylinders and having pivotal connections with the tiltable body, a duct member connected to the cylinders and having ducts which connect the upper and lower ports together in pairs, said cylinders also having check valve controlled lead ports in their upper ends above the first mentioned ports which are in communication with the cylinders and the ducts of the duct member, a pump mounted on the duct member and intersecting the ducts thereof for pumping a fluid medium within the cylinders from one side of the pistons to the other to move the pistons to predetermined positions of rest, said positions of rest of the pistons closing the ports which are supplying the fluid medium to the pump and thereby automatically stopping the movement of the pistons, and a valve controlled duct in communication with the duct member ducts to permit the passage of the fluid medium from one side of each piston to the other side without passing through the pump.

8. A fluid hoist, comprising a support, a tiltable body mounted thereon, a pair of cylinders fulcrumed on the support at their upper ends and connected together at their lower ends and having ports formed in their upper and lower end portions, a tank connected to both cylinders, pistons within the cylinders and between the ports of the respective cylinders and having piston rods extending upwardly through the cylinders and having pivotal connections with the tiltable body, a duct member connected to the cylinders and having ducts which connect the upper and lower ports together in pairs, said cylinders also having check valve controlled lead ports in their upper ends above the first mentioned ports which are in communication with the cylinders and the ducts of the duct member, a pump mounted on the duct member and intersecting the ducts thereof for pumping a fluid medium within the cylinders from one side of the pistons to the other to move the piston to predetermined positions of rest, said positions of rest of the pistons closing the ports which are supplying the fluid medium to the pump and thereby automatically stopping the movement of the pistons, a tank having openings in free communication with the cylinder bores for receiving, holding and returning to the cylinders the at times surplus fluid medium, and a valve controlled duct in communication with the duct member ducts to permit the passage of the fluid medium from one side of each piston to the other side without passing through the pump.

9. A fluid hoist, comprising a support, a tiltable body mounted thereon, a pair of cylinders connected together at their lower ends and having fulcrum recesses adjacent their upper end portions, trunnions mounted on the support and extending into the re-

cesses, said cylinders also each having an upper and a lower port, a tank connected to both cylinders, a piston within each cylinder between the ports thereof and having a piston rod which extends upwardly through the cylinder, a pivotal connection between the upper ends of the piston rods and the tiltable body, a duct member connected to the cylinders and having upper and lower horizontally extending ducts, the upper ducts of the member being in communication with the upper ports of the cylinders and the lower duct of the member being in communication with the lower ports of the cylinders, 5 a pump mounted on the duct member and intersecting the ducts thereof for pumping a fluid medium within the cylinders from one side of the pistons to the other to move the pistons to predetermined positions of 10 rest, said position of rest of the pistons closing the ports which are supplying the fluid medium to the pump and thereby automatically stopping the movement of the pistons, said cylinders also having check valve controlled 15 lead ports in their upper ends above the first mentioned ports which are in communication with the cylinders and the ducts of the duct member, said duct member also having a by-pass duct connecting the two 20 member ducts together to permit the passage of the fluid medium from one side of each piston to the other side without passing through the pump, and a valve intersecting the by-pass duct and controlling the flow of 25 the fluid medium therethrough.

10. A fluid hoist, comprising a support, a tiltable body mounted thereon, a pair of cylinders connected together at their lower ends and having fulcrum recesses adjacent 30 their upper end portions, trunnions mounted on the support and extending into the recesses, said cylinders also each having an upper and 35 a lower port, a tank connected to both cylinders, a piston within each cylinder between the ports thereof and having a piston rod 40 which extends upwardly through the cylinder, a pivotal connection between the upper ends of the piston rods and the tiltable body, a duct member connected to the cylinders and having upper and lower horizontally 45 extending ducts, the upper ducts of the member being in communication with the upper ports of the cylinders and the lower duct of the member being in communication with the lower ports of the cylinders, a pump 50 mounted on the duct member and intersecting the ducts thereof for pumping a fluid medium within the cylinders from one side of the pistons to the other to move the pistons to predetermined positions of rest, 55 said positions of rest of the pistons closing the ports which are supplying the fluid medium to the pump and thereby automatically stopping the movement of the pistons, said cylinders also having check valve controlled 60 lead ports in their upper ends above the first mentioned ports which are in communication with the cylinders and the ducts of the duct members, said duct member also having a by-pass duct connecting the two 65 member ducts together to permit the passage of the fluid medium from one side of each piston to the other side without passing through the pump, a tank mounted on the upper portions of the cylinders and having 70 openings in communication with the cylinder bores for receiving, holding and returning to the cylinders the at times surplus fluid medium, and a valve intersecting the by-pass duct and controlling the flow of the 75 fluid medium therethrough.

In testimony whereof, I affix my signature.

JULIUS P. HEIL.
